PRINTING TELEGRAPH APPARATUS

Charles W. Burcky, Chicago, Ill., assignor to Teletype Corporation, Chicago, Ill., a corporation of Delaware

Application May 25, 1936, Serial No. 81,580

16 Claims. (Cl. 178—4)

The present invention relates to printing telegraph apparatus and more particularly to such apparatus capable of tabulation recording.

In printing telegraph systems employing recording apparatus provided with tabulating mechanisms, time is necessarily required to move the type carriage or platen carriage from one position to another during tabulation. In manual operation of key controlled recording apparatus, 5 cognition is taken of the tabulating time by the operator, who, during such time, refrains from further operation of the keyboard. However, in automatic operation of such recording apparatus, by means of tape transmitters where- 10 in the apparatus is unattended for extended periods of time, it is desirable to simulate manual control during tabulation so as to suspend transmission automatically during the time that the carriage is in motion while tabulating, thus preventing the improper operation of the recording 15 apparatus.

It is the principal object of this invention to provide an efficient and smoothly operating tabulating device selectively responsive to code combinations of signaling impulses from an automatic transmitter for controlling tabulation recording and operable automatically to suspend signal transmission during tabulation operations.

A feature of the invention resides in providing 20 on the tabulator bar of a transmitter-control printer an extension which opens a contact in the circuit of the transmitting distributor when the tabulator bar is in its effective position and the carriage is in motion. When the carriage reaches a tabulator stop, and cams the tabulator 25 bar forward, the contact again closes to establish a condition for releasing the transmitting distributor.

The above and other objects of the invention 30 are accomplished by the provision in a printing telegraph apparatus, of the type disclosed in U. S. Patent No. 1,904,164, of a tabulator bar which extends across the front of the machine and is carried by brackets mounted in the typing 35 unit and capable of swinging toward and away from the type carriage. The tabulator bar carries a number of adjustable members which determine the positions to which the type carriage is automatically spaced a plurality of character 40 spaces upon the reception of a tabulator code signal combination. The spacing mechanism of the printing apparatus comprises a multi-toothed ratchet adapted to cooperate with a pair of pawls which are actuated by the printing bail to function as an escapement mechanism, so that upon

each revolution of the main shaft, the spacing worm gear associated with the spacing ratchet is permitted under normal operating conditions to escape one tooth at a time, and hence to rotate through a corresponding angle.

According to the aforementioned patent, a series of function levers is provided which operate in accordance with the setting of the series of selector vanes. Within this series of function levers, the present invention contemplates the provision of a tabulating function lever which, when selected, is drawn forward into the selector vanes under spring tension. When this occurs, the rear extension of the function lever raises and thereby lifts the rear end of a horizontal lever member. When the rear end of this horizontal lever is raised, it lifts, through suitable linkage, the upper spacing pawl out of engagement with the tooth of the spacing ratchet, at which time the front end of said horizontal member is lowered, thereby unlatching the tabulating bar to permit the latter to be biased by its spring toward the type carriage. When the upper space pawl is thus disengaged, the lower space pawl returns to its normal position free of the teeth on the escapement ratchet, which permits the spacing worm to make one complete revolution instead of only one-third of a revolution during the time that the main shaft rotates through one revolution, and, therefore, the carriage will be spaced continuously a distance, per revolution of the main shaft, which is three times that of normal spacing distance. To bring the carriage to rest after tabulating, the upper space pawl is permitted to drop again into engagement with a tooth on the spacing ratchet. This latter function is effected by the coaction of a cam element 30 assembled to the carriage and one of the adjustable members carried by the tabulator bar. This cam forces or cams the tabulator bar forward or away from the carriage, against spring tension, and in so doing permits said horizontal member to be restored to its normal position into latching engagement with the tabulator bar. This restoration action of the horizontal member 35 permits the upper space pawl again to fall into engagement with a tooth on the spacing ratchet, which thereupon brings the carriage to rest.

During the time in which the carriage is moving automatically from stop to stop during tabulation, it is necessary to suspend transmission of signals to the printer, and accordingly the present invention provides an arm depending from the tabulator bar which cooperates with a bell crank lever to control a contact in the operating circuit

for the start magnet of the transmitting distributor. Thus, when the tabulator bar is unlatched by the horizontal lever upon the selective operation of the tabulator function lever, the 5 depending portion on the tabulator bar acts through the bell crank lever to open the contact in said start magnet circuit so that, as the carriage is traveling to the next tabulator stop, transmission of signals from the transmitting distributor to the receiving printer is suspended. When the carriage has reached the tabulator stop and has cammed out the tabulator bar, the 10 depending arm will, through the bell crank lever, permit the contact in the start magnet circuit of the transmitting distributor to close, thereby 15 again initiating rotation of the transmitting distributor.

A better understanding of the invention may be had from the following description, taken in conjunction with the accompanying drawing, 20 wherein,

Fig. 1 is a front elevational view of the principal portion of the printing apparatus showing the application of the tabulating mechanism thereto, 25 supplemented with a schematic circuit diagram illustrating the relation between the transmitting distributor and the transmitter-control printer;

Fig. 2 is a transverse sectional view of the printer taken approximately on line 2—2 of Fig. 1; 30 Fig. 3 is a cross-sectional detail view taken approximately on line 3—3 of Fig. 1; and

Fig. 4 is a sectional detail view taken on line 4—4 of Fig. 1.

In the accompanying drawing, like reference 35 characters indicate similar parts throughout the several figures. For a complete understanding of details not disclosed herein and which form a part of the present invention, reference should be made to U. S. Patent No. 1,904,164 issued April 40 18, 1933 to S. Morton, et al.

A typing unit, indicated generally in Fig. 1 includes a primary selecting mechanism represented by single selector magnet 11, shown in Fig. 1, and is of the T-shaped sword lever type disclosed in 45 U. S. Patent No. 1,745,633 to S. Morton, et al. (fully disclosed in the first mentioned patent), and a secondary selector or selector vane assembly indicated generally as 12. The selector vane assembly 12 controls, through a set of bell cranks 50 13 (Fig. 1), a corresponding set of curved code bars 14 carried in a movable type carriage indicated generally at 15. As set forth in the first mentioned patent, this type carriage is movable longitudinally with respect to a stationary platen, 55 not shown, but manifestly the invention is not limited in its application to such apparatus.

Referring particularly to Fig. 2, a motor (not shown) supplies power to a main operating shaft 16 which carries the spacing mechanism indicated 60 generally 17, as well as the selector cam assembly (not shown) which cooperates with the selector magnet 11. The spacing mechanism 17 controls, through gear 18, shaft 19, gear 21, and rack 22 (Fig. 2), the successive advancement of the type carriage 15, winding as it does so a carriage return spring mechanism (not shown) which restores the carriage to its normal position upon the receipt of a carriage return signal.

Parallel to the main operating shaft 16 is an auxiliary shaft 23 on which are carried various mechanisms, for example, printing bail 24, function lever bail 25, and the escapement elements of the spacing mechanism 17. The printing bail 24, which is actuated by a spring 20, at the proper 75 time in the operative cycle, functions to recipro-

cate a pull bar operating member 26 to cause, through a pull bar 27, the operation of a particular type bar 28.

The selector vanes 88 control a series of function levers, including a tabulating function lever 29. The several function levers are pivoted on a common pivot rod 31 and are aligned within slots in a function lever comb 32. Each function lever has an individual spring 33, tending to rotate it clockwise about pivot 31, but is restrained by the 10 function lever ball 25 acting through rod 34 on arm 35. Function lever 29 is provided on its arm 36 with code notches and projections which co-operate with the vanes of the selector vane assembly 12 and which are coded to correspond to 15 the tabulator signal.

In Fig. 2 there is shown mounted on the main shaft 16 a sleeve member 37, which comprises, integral therewith, a ratchet 38 and a spacing worm 39 meshed with gear 18. Sleeve member 20 37 is operably connected to the shaft 16 by means of a friction clutch (not shown), and through which it is rotated by main shaft 16, unless blocked by the pawls of the spacing mechanism 17, as will presently appear.

Referring to Fig. 2, it will be noted that ratchet 38 is provided with three teeth 41, 42, and 43, the escapement of which will allow the type carriage 15 to be moved forward one step or character space for each actuation of the printing bail 24. 30 As indicated, the escapement mechanism comprises a pair of pawls or levers 44 and 45 pivotally mounted on shaft 23 and a lever 46 carried by the printing bail 24. Spring 47 normally tends to bias levers 44 and 45 attrahently, since it is common to both levers. Lever 44 is normally urged by spring 47 in a counter-clockwise direction so that its laterally disposed end 48 engages tooth 41 of ratchet 38, thus arresting the rotation of said ratchet. Lever 45 is normally held out of 40 engagement with ratchet 38, opposing the tension of spring 47 by the intervention of lever 46, whose free end extends into the path of laterally disposed end 49.

Lever 46 is pivotally connected at 51 to printing 45 bail 24 and is provided at 52 with a slot and screw adjusting means, whereby, in well known manner, the correct relative position of escapement levers 44 and 45, with respect to ratchet 38, may be determined.

The spacing operation occurs immediately following or subsequent to the printing of a character in the following manner.

To print a character, the printing bail 24 oscillates and in so doing controls the operation 55 of lever 46. During the initial portion of the clockwise movement of arm 46, lever 45, under the action of spring 47, also rotates clockwise to bring the laterally disposed end 53 into the path of tooth 42. It is noted that, due to the 60 space indicated at 54 between lever 46 and laterally disposed end 55 of lever 44, the latter will not be acted upon, and end 48 thereof remains in engagement with tooth 41. However, upon the further clockwise movement of lever 46, the end 65 of arm 55 is encountered and for this reason, similar movement is then imparted to lever 44, effecting the disengagement of end 48 from tooth 41 and permitting ratchet 38 to rotate slightly in a clockwise direction under the influence of 70 friction clutch members which are situated between sleeve 37 and shaft 16. This motion is limited by the engagement of tooth 42 with laterally disposed end 53 of lever 45, which lever, as was noted, was free to rotate in a clockwise di- 75

rection under the tension of spring 47. Ratchet 38 is, therefore, restrained from rotation by lever 45, while the character is being printed, after which time printing bail 24 and associated lever 46 rotate in a counter-clockwise direction actuated by a printing cam (not shown) carried on shaft 16. Restraint upon lever 44 by lever 46, through end 55, is thereby removed, permitting lever 44 to rotate in a counter-clockwise direction under the influence of spring 47 into the path of oncoming tooth 43 of ratchet 38. During this counter-clockwise movement of lever 46, and after the aforementioned removal of restraint upon lever 44, lever 45 is caused to rotate 15 in a like direction due to the action of lever 46 on laterally disposed end 49 thereof, thereby disengaging end 53 of lever 45 from tooth 42 and allowing ratchet 38 to continue its rotation until arrested by the engagement of end 48 of lever 20 44 with tooth 43. It is observed that as a result of the escapement mechanism just described, there is a period of overlap during which ends 48 and 53, due to the space indicated at 54, are effective simultaneously to prevent the escapement of ratchet 38, the ends 48 and 53 being otherwise alternately engageable to permit the escapement of ratchet 38.

It is obvious that since spacing worm 39 and ratchet 38 are integrally connected to sleeve 37, the worm 39 will have normally the same intermittent or step-by-step motion, as was hereinbefore seen to be imparted to ratchet 38. Worm 39 is meshed, as previously mentioned, with worm gear 18, which is rotatable on vertical shaft 19 and may be operably connected thereto through the instrumentality of a jaw clutch 56. Worm 39 and gear 18 are so related, according to the present embodiment, that one-third revolution of worm 39 will rotate gear 18 through a distance which, through gear 21 and rack 22, causes the type carriage 15 to be advanced the distance of one character space.

From the foregoing, it will be observed that character spacing occurs automatically with the printing of each character; that is, the spacing function is incorporated into the printing operation. It is well known that there is a code combination allotted to each type bar; but it is possible to employ a code combination, commonly known as the space signal, which is identified with no type bar, but which will, nevertheless, initiate the operation of the printing mechanism. Therefore, the spacing between words is accomplished, when a space signal is received, in exactly the same manner as just described, except that no type bar is operated and, consequently, there is no character printed.

In accordance with the present invention, continuous spacing may be effected upon the receipt 60 of a code combination known as the tabulating signal, the function of which is to initiate the operation of the tabulating mechanism. The mechanically operating tabulating arrangement of the present invention comprises a tabulator 65 bar 61, extending across the front of the printing apparatus as shown in Fig. 1, which is provided with depending portions 62 and 63, through which bar 61 is pivotally mounted on a bracket 64, carried in the printer frame. Thus, tabulator 70 bar 61 is adapted to be swingable toward and away from the type carriage 15. Bar 61 is also provided with a longitudinal slot 65 extending substantially the entire length of the bar, within which extend movable stop members 66, which are clamped to the bars 61 by means of screws

67 and clamps 68 (Fig. 2). As indicated in Fig. 4, these stop members 66 are usually provided with an inclined or cam portion 69, conformed to produce a quick action upon cooperating with a cam element 71 carried by the type carriage 5 15 to terminate suddenly the tabulating operation.

Tabulator bar 61 is also provided, intermediate the depending portions 62 and 63 (Fig. 1) and suitably positioned relative to function lever 29, 10 with another depending portion 72. Attached to and depending from portion 72 is a bar 73, the lower end of which is provided with an aperture 74 having its upper left-hand corner (as viewed in Fig. 2) formed so as to provide a re-entrant 15 stepped portion 75. The tabulator bar 61 normally tends to move in a counter-clockwise direction as viewed in Fig. 2, due to the action of spring 76 (Fig. 1).

Cooperating with the stepped portion 75 is one 20 arm 77 of a lever 78 pivotally carried at 79 on a bracket 81 screwed to the function lever comb 32. The extremity of arm 77 is provided with a laterally disposed portion 82 (Fig. 1) which cooperates with portion 75 of member 73. At the 25 end of arm 83 of lever 78 is carried a vertically extending member 84, the upper end of which is provided with an open-ended slot adapted to engage a pin 85 carried by the escapement lever 44.

Function lever 29 is provided with a horizontal 30 portion 86 so conformed that its extremity 87 engages the lower edge of arm 83 of lever 78 so that, when function lever 29 (upon its selection) is permitted to rotate in a clockwise direction under the action of its spring 33, the end 87 thereof is raised, 35 causing lever 78 to rock in a clockwise direction against the tension of its spring 89. The end 82 of arm 77 is thereby moved downwardly clear of portion 75, permitting spring 76 to urge the tabulator bar 61 inwardly (or toward the left as viewed 40 in Fig. 2) until wall 91 of member 73 engages portion 82. Adjustable stops 66 are, therefore, moved inwardly into the path of a cam member 71 (Fig. 4), which is pivoted at 92 on a portion 93 integrally formed on a bar 94, which is comparable 45 to bar 53, shown in Fig. 1 of Patent No. 1,904,164, and which is employed for retaining the bell crank levers 13 in operable relation to vanes 88. Cam 71, like bar 94 and bell cranks 13, is movable with the type carriage 15 for carriage spacing and 50 normally tends to rotate in a clockwise direction about pivot 92 due to the action of the spring 95, but its clockwise rotation is limited by the coaction of stop pin 96, carried thereon, with the end of bar 94. Consequently, upon the rightward movement 55 of type carriage 15 (as viewed in Figs. 1 and 4), cam 71, due to its limited rotatability in a clockwise direction, will, by its camming action on stop member 66, rock tabulator bar 61 outwardly; but upon the leftward movement of type carriage 15, cam 71, upon striking the series of 60 stop members 66, will be rotated counter-clockwise against the action of spring 95, avoiding the cam portion 69.

Upon the clockwise rotation of lever 78, due to 65 the selection of function lever 29, arm 83, and consequently member 84 carried thereon, will be raised, and in so doing will, through pin 85, lift escapement lever 44 out of engagement with the teeth of the ratchet wheel 38 which, since the 70 lever 45 is (after its oscillation by bail 24) prevented from engaging the teeth of the ratchet 38 due to its being held in its retracted position by lever 46, permits the worm gear 39 to make one complete revolution instead of one-third of a 75

revolution during the time that the main shaft 16 rotates through one revolution. The carriage will be spaced continuously a distance per revolution of the main shaft which is three times that 5 of normal spacing, so long as the escapement lever 44 is held out of operative engagement with lever 38, which is maintained in this position due to the engagement of lug 82 with the under side 10 of step portion 75. Thus, carriage 15 will be moved continuously until cam 71 coacts with one 15 of the series of stops 66, when, through stop 66, cam 71 will urge tabulator bar 61 outwardly, or in a clockwise direction as viewed in Fig. 2, to disengage lug 82 from portion 75, whereupon lever 18 will again be rotated in a counter-clockwise 20 direction by its spring 89 into the position shown in Fig. 2. Then member 84 carried on arm 83 of lever 18 will again be lowered, permitting escapement lever 44, under action of spring 47, to engage one of the teeth 41, 42, or 43 of ratchet 38.

The function lever 29, however, will be returned to its unselected position (as shown in Fig. 2), at the completion of the first revolution or cycle of 25 operation of the main shaft 16, because of the fact that during the cycle the function bail 25 will have been reciprocated once so that rod 34, upon the down stroke of bail 25, will permit spring 33 to urge lever 29 into cooperative relation with vanes 88 only long enough to effect the selection and the 30 resulting dislodging of pawl 44. Following this, rod 34 will cam the function lever 29 away from the vanes 88, where it will be held until the reception of another code signal.

It is manifest that during the time that the 35 carriage 15 is moving to effect tabulation, that is, from the time the tabulation signal is received up to the time when cam 71 engages the next stop 66, it is desirable to prevent the transmission and reception of succeeding character code signals, 40 inasmuch as signals sent or received during the extensive movement of the type carriage during tabulation may not properly effectuate printing. This is especially true in connection with automatic transmission. Hence, it is an object of the 45 present invention to provide means for suspending the transmission of code signals during the tabulation operation. Accordingly, the tabulator bar 61 is provided with a depending tongue or portion 101 (Fig. 1), the lower end of which 50 operates with a bell crank 102 pivoted at 103, Fig. 3, to a base 104. Arm 105 of bell crank 102 coacts with an insulated button 106 of a contact pair 107 mounted on a bracket 108 fixed to member 64. The pair of contacts 107 is connected in 55 a circuit including a start magnet 109 of a transmitting distributor indicated generally 111.

The transmitting distributor which may be of the structure disclosed in U. S. patent to Klein- 60 schmidt No. 1,632,297, comprises a set of tape sensing elements 110 which, under the control of a tape or signal storing medium 97, control a corresponding series of contacts 112, which are connected from a common ground over individual conductors 113 to segments 114 of a sunflower type distributor 115, which has a rotary transmitting arm 116 adapted to traverse the segments 114. The arm 116 is arrested cyclically by a stop lever 117 controlled by the 65 magnet 109. The inner ring 118 of the distributor 115 is connected by means of conductor 119 to the selector magnet 11, and in the event that a series of printers are connected to the transmitter, the selector magnets 11 therein are interconnected in series by the line wire 121.

General operation

When the manual switch 122 is closed, an energizing circuit for start magnet 109 is completed from battery 123, over conductor 124, through the windings of start magnet 109, over conductor 125, through the pair of contacts 107, thence over conductor 126 and through switch 122 back to battery. In this operating condition, the transmitting distributor is free to rotate and transmits signals to the printers connected to the line in accordance with the permuted operation of contacts 112 under the control of the perforated tape 97. During the reception of character signals, the carriage 15 is advanced in a step-by-step manner for normal character spacing. However, upon the receipt of a tabulator signal, the selector vanes 88 will be correspondingly positioned through the instrumentality of the selector mechanism of which selector magnet 11 is a part, to effect the selection of function lever 29. As clearly described in the Patent No. 1,904,164, the main shaft cams are initiated into operation in proper time relation with the start signal of the start-stop code signals, and at the proper instant after the reception of the code signal, the shaft 16 is rotated to permit the oscillation of printing bail 24 and also function bail 25. Upon the downward movement of function lever bail 25, function lever 29 is permitted to respond to its spring 33 to be biased into selective cooperation with the vanes 88. This movement of function lever 29 causes its end 87 to be raised to impart clockwise rotation to lever 18, which, through member 84, causes pawl 44 to be disengaged from tooth 41, and substantially simultaneously therewith causes end 82 to be disengaged from shoulder 75, the latter disengagement permitting tabulator bar 61 to be drawn toward the printer by its spring 76, thus bringing the stops 66 into the path of pawl 71. Upon the movement of bar 61, tongue 101 will, through bell crank 102, cause the pair of contacts 107 to be opened, and thereby break the energizing circuit for start magnet 109 to effect the arrestment of distributor arm 116 by arm 117. Thus, 25 it is noted that upon the receipt of the tabulator signal, not only is the tabulator bar actuated into cooperative relation with the pawl 71, but also the pair of contacts 107 are opened 30 to suspend transmission during the performance of the tabulation operation.

The return of the printing bail 24 and function lever bail 25, after oscillation, to its position shown in Fig. 2 will cause the function lever 29 to be returned to its counter-clockwise position. But pawl 44, due to the blocking of end 82 of lever 18 by shoulder 75, will remain out of engagement with ratchet 38, thus permitting the shaft 16 to rotate freely to cause the continuous movement of carriage 15 through spacing worm 39 until pawl 71 reaches the next stop 66, at which time, due to the camming action of pawl 71 and cam portion 69, the tabulator bar 61 will be urged outwardly and the arm 73 will be actuated inwardly (or in a clockwise direction as viewed in Fig. 2) to cause simultaneously the contact 107 to be again closed and the lever 18 to again assume its position shown in Fig. 2, whereby the pawl 44 is brought into engagement with the teeth 41, 42, or 43 of ratchet 38. The closing of the pair of contacts 107 again initiates, through the energization of starting magnet 109, the operation of the transmitting distributor 111. All of the receiving 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

printers connected to the line will be correspondingly operated.

It is understood that many changes may be made in the details set forth in the foregoing description without departing from the essentials of the invention or from the spirit and scope of equivalency thereof, as defined in the appended claims.

What is claimed is:

- 10 1. In combination, transmitting means effective under the control of a signal storing medium, a distributor having a normal rest position, a recorder responsive to signaling conditions from said transmitting means, tabulating mechanism, and means in said recorder controlled by said tabulating mechanism for controlling the arrest of said distributor in its normal rest position.
- 15 2. In combination, transmitting means effective under the control of a signal storing medium, means for controlling the effectiveness of said signal storing medium, a recorder responsive to signaling conditions, tabulating mechanism, and means in said recorder controlled by said tabulating mechanism for controlling the effectiveness of said second recited means.

20 3. In a telegraph system, a transmitter, a recorder having a carriage, spacing mechanism therefor, permutation code mechanism to control the operations comprising a plurality of function code levers, tabulating mechanism operative in response to the selective operation of a certain one of said levers to control, through said spacing mechanism, the advancement of said carriage through a predetermined plurality of spaces at a time, and means controlled by said tabulating mechanism for controlling said transmitter during the tabulation operation.

25 4. In a telegraph system, a transmitter, means for controlling the effectiveness of said transmitter, a receiver responsive to signaling conditions comprising a functional instrumentality, and means controlled by said instrumentality for controlling the effectiveness of said first recited means during certain periods of operation of the receiver.

30 5. In combination, a recorder having a carriage movable in accordance with character spaces, means to perform functions, a permutation device movable with said carriage to determine the character to be recorded, a stationary permutation device to control said means and said permutation device, a tabulating device controlled by said means for controlling the advancement of said carriage a plurality of spaces at a time from one recording position to another, a transmitting means controlled by a signal storing medium, means for controlling the effectiveness of said signal storing medium, and means in said recorder controlled by said tabulating device for controlling the effectiveness of said last mentioned means.

35 6. In combination, a telegraph recorder, selector mechanism responsive to code signals, a type carriage, spacing mechanism operative normally to control the advancement of said type carriage one character space at a time, tabulating mechanism effective under the control of said selector mechanism to control the advancement of said type carriage through a plurality of spaces at a time, a transmitting means effective under the control of a signal storing medium, means for controlling the effectiveness of said signal storing medium, and means in said recorder controlled by said tabulating mechanism

for controlling the effectiveness of said last mentioned means.

7. In combination, a recorder, a plurality of recording elements collectively movable normally one character space, selecting means, means controlled by said selecting means for causing said recording elements to advance continuously through a plurality of spaces at a time from one recording position to another, a transmitter, means for controlling the effectiveness of said transmitter, and means in said recorder controlled by said second recited means for controlling the effectiveness of said last mentioned means.

8. In combination, a recorder, collectively movable recording elements, means for restraining the movement of said elements to one character space, means for disabling said restraining means to enable continuous movement of said elements throughout a predetermined plurality of character spaces at a time, a transmitter, means for controlling the effectiveness of said transmitter, and means in said recorder controlled by said second recited means for controlling the effectiveness of said last mentioned means during the period of disability of said restraining means.

9. In combination, a telegraph recorder, a carriage movable to form character spaces, spacing mechanism therefor normally adapted to control the advancement of said carriage one character space, means operable in cycles to actuate said spacing mechanism normally one character space for each cyclic operation of said cyclically operable means, means to disable said spacing mechanism whereby said carriage is advanced a plurality of character spaces for each cycle of operation of said cyclically operable means, a transmitter, means for controlling the effectiveness of said transmitter, and means in said recorder controlled by said disabling means for controlling the effectiveness of said last mentioned means during the period of disablement of said spacing mechanism.

10. In a telegraph system, a transmitter operable under the control of a signal storing medium, means for controlling the effectiveness of said signal storing medium, a receiver responsive to signaling conditions comprising a functional instrumentality, and means controlled by said instrumentality for controlling the effectiveness of said first recited means during certain periods of operation of the receiver.

11. In a telegraph system, a transmitter operable under the control of a signal storing medium, sensing means for said signal storing medium, a receiver responsive to signaling conditions comprising a functional instrumentality, and means controlled by said instrumentality for controlling the effectiveness of said sensing means during certain periods of operation of the receiver.

12. In a telegraph system, a transmitter operable under the control of a tape, tape sensing mechanism, a receiver responsive to signaling conditions comprising a functional instrumentality, and means controlled by said instrumentality for controlling the effectiveness of said tape sensing means during certain periods of operation of the receiver.

13. In a control system for printing telegraph receivers comprising selecting instrumentalities and a signal responsive means for controlling the selective operation of the selecting instrumentalities, means effective for allowing free operation of said means during signaling periods, and

means controlled by the selecting instrumentalities to render said last mentioned means ineffective during predetermined periods.

14. In combination, a transmitting mechanism including a rotating part effective for causing the successive transmission of signal impulses, a recorder responsive to said signal impulses, a tabulating mechanism embodied in said recorder, and means controlled by the tabulating mechanism for controlling the operation of said part during tabulating operations.

15. In combination, a transmitting mechanism including a rotating part effective for causing the successive transmission of signal impulses, a recorder having a movable carriage responsive to said signal impulses, means in said recorder for effecting continuous spacing of said carriage, and

means operated upon the operation of said means for controlling the operation of said part during continuous spacing of the carriage.

16. In combination, a recorder having a movable carriage, means for restraining the movement of said carriage to one character space, means for disabling said restraining means to enable continuous movement of said carriage throughout a predetermined plurality of character spaces at a time, a transmitter, means for controlling the effectiveness of said transmitter, and means in said recorder controlled by said second recited means for controlling the effectiveness of said last mentioned means during the period of disability of said restraining means. 15
